CLAIM

The ornamental design for a decorative wall block, as shown and described.

DESCRIPTION

FIG. 1 is a perspective view of the decorative wall block of the first embodiment, the block having quarter round voids at the two front corners of the block;

FIG. 2 is a rear view of the block of the first embodiment;

FIG. 3 is a top view of the block of the first embodiment;

FIG. 4 is a front view of the block of the first embodiment;

FIG. 5 is a bottom view of the block of the first embodiment;

FIG. 6 is a left end view of the block of the first embodiment, the end view enlarged to show one of the quarter round voids having scrape marks therein;

FIG. 7 is a right end view of the block of the first embodiment, the end view enlarged to show one of the quarter round voids having scrape marks therein;

FIG. 8 is an enlarged perspective view of the right hand portion of the block of FIG. 1, the quarter round void having scrape marks therein;

FIG. 9 is a perspective view of the right hand portion of a block of a second embodiment, the quarter round void being smooth therein, the left hand portion having a similar void; and,

FIG. 10 is a perspective view of the right hand portion of a block of a third embodiment having a quarter square void at the front right corner, the left hand portion having a similar void.
